UNITED STATES PATENT OFFICE

2,123,838

LOUVER FOR RAILWAY CARS

Brunolf C. Baade, Akron, Ohio, assignor to Good-year-Zeppelin Corporation, Akron, Ohio, a corporation of Delaware

Application April 3, 1936, Serial No. 72,671

10 Claims. (Cl. 105—61)

The present invention relates to cooling systems and the like and particularly those cooling systems used on railroads for cooling the water used for cooling the motor. Such cooling systems may also be used for the cooling of the oil supplied to the motor or for various other purposes.

The primary object of this invention is to control the louvers which direct the air over cooling coils or the like in a manner to insure the efficient flow of air through and around the coils whichever direction the train is traveling.

A particular object of this invention is to control the louvers by at least a portion of the mechanism used to start the train so that whenever the train is operated the louvers are automatically positioned in the proper relation to insure efficient cooling.

My invention is particularly applicable to trains of the double-ended variety, that is trains which are equipped to be driven from either end, thus requiring a change of the positions of the louvers when the train is driven in opposite directions.

Another object of this invention is to provide a louver-control mechanism which must first be placed in operation before the main motor control circuit can be operated. Such a mechanism is preferably placed at each end of the train so as to automatically control the louvers when the train is started from either end.

In the drawings,

Figs. 1 and 2 are fragmentary sections of opposite ends of a train equipped with my invention;

Fig. 3 is a cross-section taken substantially along the line 3—3 of Fig. 2;

Fig. 4 is an enlarged fragmentary side view of a portion of the train illustrated in Fig. 3 with parts broken away to show the louvers at the top of the train;

Fig. 5 is in part a horizontal cross-section taken substantially along the line 5—5 of Fig. 3; and

Fig. 6 shows a detail of the louver mounting.

In Figs. 1 and 2 the reference character 10 indicates the train generally including the trucks, wheels, etc., the same being provided with pivoted louvers 11 in the roof of the train and louvers 12 on the side thereof. Each side of the train is equipped with substantially identical louvers and control means therefore and a description of the one will suffice for all of them, one side only being shown.

Referring particularly to Fig. 4, it will be noted that the louvers 11 are each pivoted as at 13 to swing about an axis at a slight angle to the horizontal. The louvers are slightly curved in cross-section so that as they catch the air it will be

drawn through the cooling system with a minimum effort. Note that these louvers are all within the confines of the outer contour of the body so as not to set up what is called a parasite air resistance. Similarly, the louvers 12 are pivoted at 14 so as to move about a substantially vertical axis.

In order to control the louvers 11 simultaneously, the same are connected by a rod 15 pivotally connected to arms 16 extending inwardly from the inner surface of the louvers. It will be seen from an inspection of Fig. 4 that movement of the rod 15 to the right will cause the louvers to be pivoted about their axes to a position such that they occupy a reversed position, namely that which is shown in Fig. 2. Similarly, the louvers 12 are controlled by a rod 17 pivotally connected to each of the arms 16 on the louvers and by longitudinal movement of this rod these louvers are caused to move to a reverse position as is illustrated by dotted lines in Fig. 5.

Located inside the train adjacent the louvers are coils 19, 20 and 21, which may be used for the circulation of air, oil, or any other medium. The louvers form the opposite ends of a passage defined by the outer wall of the train and the inner passage walls 22 so that the air will be directed into the passage through one louver and out through the other. Arranged within each of the passages is a fan 23 driven by motor 24 which causes the air to circulate in a given direction through the air passage. This motor is preferably driven in one direction at all times independently of the direction of movement of the train. In the instance shown the air is caused to move from the louvers 12 at the side through the passage and out through the louvers 11.

Ordinarily, the louvers at the head end of the train (namely that end which forms the forward end of the train depending upon the direction the train is moving) occupy the wrong position to insure the proper circulation of the air. However, this makes the louvers at the opposite end of the train be in proper position for proper handling of the air, so it is only necessary to change those louvers at the forward end in order to have correct ventilation for both ends of the train if the air-cooling equipment at both ends is to be used.

For example, Fig. 1 shows the head of the train if it is considered that the train is moving to the left, and Fig. 2 shows the head of the train if the train is considered as moving to the right. Assuming that the train is to be driven to the right or from the end of the train shown in Fig. 2, the louvers are facing in the wrong direction for the

side louvers should have their leading edges forwardly and the louvers at the top should have their trailing edges to the rear, as in Fig. 4, which is just reversed in Fig. 2. It is therefore necessary to provide means for reversing the positions of these louvers before the train is set in motion.

Obviously, as will be seen from an inspection of Fig. 2, when the train is moving to the left the louvers shown in this figure are arranged in the proper position for controlling the flow of air through the cooling coils and they do not have to have their direction changed when the train is started.

Ordinarily, when the train is at rest, the louvers are as illustrated in Figs. 1 and 2. The louvers at the rear being in the proper position and the louvers in the front being in the improper position, regardless of which direction the train is to be run. I, therefore, propose to control the louvers at the head end of the train so that they will be placed in proper position, preferably at or before the time the train is started. In the present instance, I have illustrated means which compels the operation of the louvers at the head of the train into their proper position before the train itself may be started. This means comprises an electrical hook-up diagrammatically illustrated in Fig. 3, but could comprise mechanical means for accomplishing the same purpose.

In actual use a more complicated electrical system than that illustrated is used but that illustrated is used merely for the purpose of illustration.

The rods 15 are each connected to bell cranks 26 pivoted as at 27, which are in turn pivotally connected to rods 28 on the end of each of which there is provided a piston 29. This piston operates within a cylinder 30 and is normally urged in a downwardly direction by a spring 31. Air or fluid under pressure is introduced into the lower end of the cylinder 30 when desired through a conduit 32 to force the piston 29 upwardly. This conduit 32 has a valve 35 provided with a control arm 36 pivotally connected, as at 37, to a core 38, operating within a solenoid 39. Whenever the solenoid 39 is energized, the operating arm 36 is moved to admit fluid under pressure to the lower end of the piston, thus raising the rod 28, and through the intermediacy of the bell crank 26 and the rod 15 the louvers 11 are pivoted into the position illustrated in Fig. 4 with their leading edges forward. When the solenoid is deenergized the spring 31 moves the louvers to their normal positions illustrated in the drawings.

Similarly, the louvers at the side are controlled by bell crank 40 which shifts the rod 41 to reverse the position of the louvers and operating rod 41 for operating the bell cranks 40 and a second bell crank 42 for moving the rod 41. One arm of the bell crank 42 is pivotally connected to the rod 28 so that when the latter moves upwardly the result is that not only are the louvers at the top of the car released and placed in proper position, but also the louvers at the side so that the air will be drawn in through the louvers at the side of the car and directed upward to the louvers at the top of the car, which latter louvers discharge the air toward the rear of the train so that there is a natural flow of the air as the train moves forward.

It is important that these louvers be placed in proper position before the train starts, or at least simultaneously with the starting of the train so that as the train moves forward the louvers will not direct the air in a direction opposed to the

direction of movement of the air caused by the fans 23, for this would have the tendency to neutralize the action of the fans and place an unnecessary load on the motors. The simple electrical diagram shown in Fig. 3 illustrates one means for insuring that the control circuit for operating the motors which drive the train must be operated in such a way as to move the louvers into proper position before the train is started.

The motor M which drives the train is driven from a generator G, the latter in most instances being in turn driven by a Diesel-type engine.

The motor M is connected by lead 43, rheostat 44, lead 45, switch 46 and lead 47 to the generator G. In the position shown in the drawings the rheostat switch 48 is in the "off" position and, therefore, forms one break in the motor circuit. The switch 46 is also open and, therefore, forms another break in the motor circuit. Therefore, when the rheostat switch 48 is moved to any of the "on" positions the motor will not start unless the switch 46 is closed. The switch 46 is closed by the action of a solenoid 49 when the circuit including the solenoids 39 and 49 is closed by means of the switch 50. The closing of the switch 50 causes the actuation of the control arm 36 for the valve 35 whereby the louvers 11 and 12 are moved to their proper position. At the same time the switch 46 is closed by the action of the solenoid 49, thereby completing the motor circuit except through the rheostat. Therefore, when the control arm 48 of the rheostat is moved to any of the "on" positions thereof the motor circuit is completed and the train will start. In other words, it will be noted that the louvers must first be placed in the proper position before the train can be started, or at least the train cannot start until the louvers have been moved to the proper position. The starting of the train may be simultaneous with the action of the louver if the rheostat is first connected and the switch 50 is thereafter actuated, but preferably the circuit is so arranged that the switch 50 must be actuated before the rheostat switch 48 can be actuated. This is not shown in the drawings but the manner in which it may be accomplished is readily apparent to any one skilled in the electrical art. The switches 48 and 50 may even be controlled by a single operating handle to be operated in succession or even simultaneously. The form of the invention illustrated in the drawings, however, is sufficient to illustrate one control means for my invention.

In operation the motorman closes the switch 50 at the head end of the train and this throws the louvers at that end of the train into proper position, those louvers at the rear already being arranged in the proper position for forward movement of the train. He then actuates the rheostat switch or control switch for starting the train and for driving same at the desired speed.

After the train has been operated in one direction and it is desired to operate the train in the opposite direction the motorman goes to the other end of the train and operates that end in the same manner. Suitable interconnecting means are preferably provided to connect the drive at both ends of the train so that if the switch 50 at the rear end of the train is not open the train will not start, for it is essential that the switch 50 at the rear end of the train be open so that the louvers at that end of the train will occupy their normal position, which is the correct position for the forward movement of the train.

In Fig. 6 I have shown a detail of the pivotal mounting for the louvers in which there is a pintle 51 secured to the louver 11, this pintle rotatable in a suitable bearing 52 in the bracket 53. 5 Of course any other form of pivotal mounting may be provided as this is not an essential feature of applicant's invention.

Applicant's invention could be readily modified by having the control circuits at both ends interlocking to positively move both sets of louvers at the front and rear of the train into proper position before the train is started. Then when the train is operated in the opposite direction the control circuit is such that these louvers at both ends are again moved to position the same in the proper position for movement of the train in the last-mentioned direction. However, with applicant's arrangement, one set of louvers is always in proper position and it is only necessary to actuate the other set. Obviously, those skilled in the art to which this invention pertains may make various changes in the particular arrangement of the parts without departing from the spirit of this invention and, therefore, I do not wish to be limited in my invention except as may hereinafter be pointed out in the claims hereunto appended.

Having thus fully described my invention, what I claim and desire to secure by Letters Patent of the United States is:

1. In a device of the class described, the combination with a train having a conduit arranged therein, the ends of which communicate with the exterior surface of said train, an air-circulating means for driving the air through said conduit in one direction only, coils arranged in said conduit and louvers at the ends of said conduit for directing the air into and out of said conduit, and means for maintaining said louvers normally in one position so as to properly and efficiently direct the air from the surrounding atmosphere through said conduit in the direction said air is normally moved by the said air-circulating means, when the train moves in one direction, means for reversing the positions of said louvers whereby to direct the air through said conduit in the same direction when said train is operated in the opposite direction and means for compelling the actuation of said last-mentioned means upon actuation of said train in the said last-mentioned direction.

2. In a device of the class described, the combination with a train, of an air conduit thereon through which air is to be directed while the train is in motion, movable louvers for at least one end of said conduit for guiding the air in the desired direction through said conduit from the surrounding atmosphere when in one position thereof and while the train is in motion, means for controlling the driving of the train, and means connected with the louvers and controlling means for compelling movement of said louvers into said position if not previously in said position at least by the time said train-operating means is operated to put the train in motion.

3. In a device of the class described the combination with a train operable in opposite directions and having a conduit, louvers arranged in said conduit and mounted for movement to either of two positions, in one of which the louvers aid in directing air through the conduit in the desired direction from the surrounding atmosphere as the train moves in one direction, but not while moving in the opposite direction, means normally

holding said louvers in one of said positions, means for controlling the actuation of said train and means compelled by said train controlling means for compelling actuation of said louvers from said normal position to the other position thereof if and when the louvers are incorrectly set for the direction in which the train is actuated.

4. In a device of the class described, the combination with a train having a plurality of conduits, at least one at each end of said train, operating means for controlling the movement of said train, at least one set of louvers associated with each conduit for directing air through the respective conduit from the surrounding atmosphere, means normally holding each set of said louvers in a position of adjustment such that one set is incorrectly arranged only in desired operative position for movement of the train in one direction and the other only for movement of the train in the opposite direction, and means connected to the train-operating means to compel operation of the incorrectly set louvers to operative position prior to starting of the train.

5. In a device of the class described, the combination with a train having a transverse air passage at each end of the train, at least one louver associated with each conduit for directing the flow of air therethrough from the surrounding atmosphere when the train is in motion, means for normally holding said louvers in such positions that for forward movement of the train in either direction the louver at the rear end of the train is in position to direct the air through its respective passage in the desired direction and the louver at the head of the train is in a position to direct the air through its respective passage oppositely to the desired direction, and means associated with the driving mechanism for the train to compel movement of the louver at the head end of the train into a position to direct air through the respective passage in the desired direction, at least by the time the mechanism for setting the train in motion is operated, said means being so arranged and constructed as to insure movement of the louvers at the head end of the train into said last-mentioned position at least by the time the mechanism for setting the train in motion is operated.

6. In a device of the class described, the combination with a train, of means for controlling the operation of said train, an air conduit within said train having the ends thereof communicating with the atmosphere outside said train at different points, power means for directing air through said conduit in one direction, louvers at each end of said conduit for directing the passage of air therethrough from the surrounding atmosphere in the same direction as by said power means while the train is in motion and while in their operative positions, means for normally holding said louvers in an operative position for the purpose set forth for movement of the train in the other direction, and means associated with said train-controlling means for compelling movement of said louvers to operative position for conveying the air in the direction of movement of the air by said directing means when the train is operated in said first direction.

7. In a device of the class described, the combination with a train, of means for controlling the operation of said train, an air conduit within said train having the ends thereof communicating with the atmosphere outside said train at different points, power means for directing air through

5 said conduit in one direction, louvers at each end of said conduit for directing the passage of air therethrough from the surrounding atmosphere in the same direction as by said power means while the train is in motion and while in their operative positions, means for normally holding said louvers in an operative position for the purpose set forth for movement of the train in the other direction, and means associated with said 10 train-controlling means for compelling movement of said louvers to operative position for conveying the air in the direction of movement of the air by said directing means when the train is operated in said first direction, said controlling means for the train being so connected to the louver moving means as to be inoperative until said louver moving means becomes operative to place said louvers in desired operative position.

20 8. In a device of the class described, the combination with a train, of an air conduit thereon through which air is to be directed while the train is in motion, a movable set of louvers for each end of said conduit for guiding the air in the desired direction through said conduit from the surrounding atmosphere when in one position thereof and while the train is in motion, means for controlling driving of the train, and means connecting both sets of louvers and said train-driving control means for compelling movement 25 of said louvers into said position, if not previously in said position, at least by the time said controlling means is operated to put the train in motion.

30 9. In a device of the class described, the combination with a train adapted to be operated in opposite directions, of a conduit at each end of said train extending from the side wall thereof to the top of the train, louvers arranged at each end of each of said conduits, means for operating the train in either direction, means for normally holding the louvers in such a position that if the train is to be operated in either direction the louvers in the conduit at the rear end of said

train are in proper position to direct the air from the surrounding atmosphere through their respective conduits in the desired direction, means for normally holding the louvers at the head end of the train in a reverse position to that required for moving the air from the surrounding atmosphere through their respective conduit in the desired direction during forward movement of the train, and means for compelling reversal of the position of said louvers at the head end of the train at least by the time said train-operating means is actuated to start said train in a forward direction, whereby to place the louvers in proper operative positions for said forward movement.

10 10. In a device of the class described, the combination with a train having means for controlling the operation thereof, of a conduit on said train communicating with the atmosphere at each end thereof, cooling coils in said conduit, means for circulating the air through said conduit and cooling coils in said conduit, louvers for directing air from the surrounding atmosphere through said conduit and cooling coils while the train is in motion, means for normally holding the louvers in a position to direct air through the 15 conduit in the desired direction when the train moves in one direction, and means operatively connected to said control means for changing the position of the said louvers when the train is actuated by said control means in the opposite direction to direct the air in the same direction through said conduit as when said train was moving in said first direction, whereby the air is directed through said conduit in the same direction regardless of the direction in which the train is moving, said last-mentioned means being interconnected with the controlling means for said train, whereby when the control means is operated, said means for changing the positions of 20 said louvers is operated in a manner such that the louvers will always be compelled to occupy 25 the desired operative positions therefor.

5 said conduit in one direction, louvers at each end of said conduit for directing the passage of air therethrough from the surrounding atmosphere in the same direction as by said power means while the train is in motion and while in their operative positions, means for normally holding said louvers in an operative position for the purpose set forth for movement of the train in the other direction, and means associated with said 10 train-controlling means for compelling movement of said louvers to operative position for conveying the air in the direction of movement of the air by said directing means when the train is operated in said first direction, said controlling means for the train being so connected to the louver moving means as to be inoperative until said louver moving means becomes operative to place said louvers in desired operative position.

20 8. In a device of the class described, the combination with a train, of an air conduit thereon through which air is to be directed while the train is in motion, a movable set of louvers for each end of said conduit for guiding the air in the desired direction through said conduit from the surrounding atmosphere when in one position thereof and while the train is in motion, means for controlling driving of the train, and means connecting both sets of louvers and said train-driving control means for compelling movement 25 of said louvers into said position, if not previously in said position, at least by the time said controlling means is operated to put the train in motion.

30 9. In a device of the class described, the combination with a train adapted to be operated in opposite directions, of a conduit at each end of said train extending from the side wall thereof to the top of the train, louvers arranged at each end of each of said conduits, means for operating the train in either direction, means for normally holding the louvers in such a position that if the train is to be operated in either direction the louvers in the conduit at the rear end of said

train are in proper position to direct the air from the surrounding atmosphere through their respective conduits in the desired direction, means for normally holding the louvers at the head end of the train in a reverse position to that required for moving the air from the surrounding atmosphere through their respective conduit in the desired direction during forward movement of the train, and means for compelling reversal of the position of said louvers at the head end of the train at least by the time said train-operating means is actuated to start said train in a forward direction, whereby to place the louvers in proper operative positions for said forward movement.

10 10. In a device of the class described, the combination with a train having means for controlling the operation thereof, of a conduit on said train communicating with the atmosphere at each end thereof, cooling coils in said conduit, means for circulating the air through said conduit and cooling coils in said conduit, louvers for directing air from the surrounding atmosphere through said conduit and cooling coils while the train is in motion, means for normally holding the louvers in a position to direct air through the 15 conduit in the desired direction when the train moves in one direction, and means operatively connected to said control means for changing the position of the said louvers when the train is actuated by said control means in the opposite direction to direct the air in the same direction through said conduit as when said train was moving in said first direction, whereby the air is directed through said conduit in the same direction regardless of the direction in which the train is moving, said last-mentioned means being interconnected with the controlling means for said train, whereby when the control means is operated, said means for changing the positions of 20 said louvers is operated in a manner such that the louvers will always be compelled to occupy 25 the desired operative positions therefor.
